UNITED STATES PATENT OFFICE

CHARLES L'ENFANT, OF NEW YORK, N. Y.

COIN PURSE

Application filed November 13, 1929. Serial No. 406,766.

This invention relates to a coin purse, and has for its general object and purpose to provide a coin purse of very simple and inexpensive construction as an accessory for ladies' handbags, or which may be independently carried in the pocket and which will enable access to be easily and quickly had to the coins contained therein and all of the coins visibly exposed for the selection of a single 10 desired coin, without danger of dropping or losing the coins.

More particularly, in the preferred practical embodiment of the invention, the purse is formed from a single sheet of leather or other 15 flexible material which is stamped or cut to provide an end portion having relatively foldable parts forming the pouch or pocket of the purse and an extension on one wall of the purse whereby said extension and the opposite 20 site wall of the purse may be readily flexed by pressure of the fingers while the purse is held in the hand so that the coins may be dislodged from the purse pocket and disposed in a scattered or separated relation upon said wall except 25 tension of the purse and after the selection of the desired coin, the remainder collectively returned to the purse pocket.

It is also another object in one embodiment of the invention to provide such a coin purse 30 made from a single sheet of flexible material provided upon its opposite end portions with foldable parts forming pockets having their open sides in opposed relation so that in the use of the purse and the selection of coins contained therein, the coins may be moved from 35 one pocket to the other. The sheet of flexible material is adapted to be centrally folded to dispose the opposed pockets in face to face contact and the walls of said pockets at their 40 open ends in contact with said central part of the flexible sheet whereby said open ends of the pocket will be securely closed and loss of the coins prevented.

With the above and other objects in view, 45 the invention consists in the improved coin purse, and in the form, construction and relative arrangement of its several parts, as will be hereinafter more fully described, illustrated in the accompanying drawings, and subsequently incorporated in the subjoined claim.

In the drawings, wherein I have illustrated several simple and practical embodiments of the device, and in which similar reference characters designate corresponding parts throughout the several views,—

Fig. 1 is a side elevation of one form of my improved coin purse showing the same closed;

Fig. 2 is a similar view showing the purse open;

Fig. 3 is an end elevation;

Fig. 4 is a sectional view taken on the line 4—4 of Fig. 1;

Fig. 5 is a plan view of the blank from which the purse is formed;

Fig. 6 is a detail fragmentary section taken on the line 6—6 of Fig. 3;

Fig. 7 is a sectional view taken on the line 7—7 of Fig. 6;

Fig. 8 is a detail fragmentary end elevation, the end wall of the purse pocket being fully expanded;

Fig. 9 is a side elevation showing a further alternative embodiment of the device;

Fig. 10 is a similar view showing the latter form of the purse open;

Fig. 11 is an end elevation of the purse folded and closed;

Fig. 12 is a sectional view taken on the line 12—12 of Fig. 9;

Fig. 13 is a plan view of the blank from which the purse shown in Fig. 9 is formed;

Fig. 14 is a detail vertical section taken on the line 14—14 of Fig. 11;

Fig. 15 is a similar view showing a slightly different arrangement of the closure means for the ends of the purse pocket, and

Fig. 16 is a perspective view illustrating the manner of using the double pocket purse shown in Fig. 10.

Referring in detail to the drawings, the invention as illustrated in its simplest embodiment in Figs. 1 to 8 of the drawings consists of a purse having a single coin receiving pocket which is produced from a single sheet of leather or other flexible material generally indicated at 5. This material is stamped or cut out by means of suitable dies to provide a blank of the requisite length and width and which includes an intermediate section 6 of

uniform width and an end section 7 at one end thereof preferably somewhat tapering in width and constituting a closure flap for the purse. At the other end of the intermediate section 6 the blank is provided with a comparatively wide end section affording portions extending laterally beyond opposite edges of the intermediate section 6, the central part of said latter end portion of the blank indicated at 8 constituting one side wall of the purse pocket. The lateral extensions of this wide end portion of the blank are adapted to be folded along the spaced oblique lines indicated at 9 so as to provide opposite expandible end walls 10 for the purse pocket, when the part 8 is folded substantially along the line indicated at 11 and disposed in opposed relation to the intermediate section 6 of the blank. The outer vertical edges of these expandible end walls 10 of the pocket are permanently secured to the edges of the section 6 which forms the other side wall of the pocket by the lines of stitching indicated at 12. The fold 11 in the material forms the closed bottom of the purse pocket, and the side wall 8 of said pocket gradually tapers or decreases in width from this closed bottom upwardly to the open upper edge of the pocket.

As clearly shown in Fig. 5 of the drawings, the laterally extending portions of the widened end of the blank from which the expandible end walls 10 of the purse pocket are formed are provided at the ends thereof contiguous to the fold 11 with the tabs indicated at 13. As shown in Figs. 6 and 7 of the drawings, these tabs extend inwardly from the lower end to the relatively flexing parts of the end walls 10 and constitute closures for the gap or space between the lower end edges of these flexible wall sections and the bottom of the purse pocket, thus effectually precluding the possible escape of small coins therethrough.

The outer side of the pocket wall 8 and the inner side of the flap 7 are preferably provided with the complementary parts of a suitable fastening means indicated at 14, whereby when the flap is folded downwardly over the upper open edge of the pocket, it may be securely fastened and detachably retained in connection with the side wall of the pocket.

It will be apparent that in view of the fact that the device above described is fabricated from a single cut or stamped sheet of flexible material, the expense of manufacture of such a device incident to the time and labor required in its production will be insignificant. By the provision of the elongated intermediate section 6 of the blank affording an extension from one of the side walls of the purse pocket, when the purse is opened and the device held in the palm of the hand, by pressure against the lateral edges of the part 6 and the end walls of the

pocket, said end walls may be expanded and the longitudinal extension of the section 6 from the side wall of the purse bowed or cupped. Thus by tilting the hand, the coins may be caused to slide from the pocket upon this wall extension whereby they are securely held against being dropped and lost. After the desired coin has been selected, the collection of coins can be readily returned to the purse pocket by disposing the latter in an upright position, after which the flap 7 is folded over the open end of the pocket and fastened in closed position.

If desired, the blank shown in Fig. 5 of the drawings may be faced or lined on one side with silk or other suitable reinforcing fabric, and the marginal edges of the blank folded inwardly and stitched to the lining sheet to provide a desired finish.

In Figs. 9 to 16 of the drawings, I have illustrated another desirable embodiment of the invention, in which the purse while still formed from a single sheet of material, is provided with two opposing pockets. Thus the blank 5 is provided with the elongated intermediate body portion 6' of uniform width and with the widened portion at each of its ends to form a pocket wall 8' and the foldable lateral extensions to form the end walls 10' of the pocket, when said end portions of the blank are properly folded with respect to the intermediate body section thereof and the edges of said end walls of the respective pockets secured to the edges of the body section in the manner above explained. It is thus seen from reference to Fig. 10 that this construction provides two pockets on the inner side of the body wall 6' having their open edges in spaced opposed relation to each other. The walls 8' of the pockets are provided with the complementary fastening elements 14' whereby said pocket walls may be separably connected with each other, when the purse pockets are folded in face to face contact as seen in Figs. 11 and 12 of the drawings. It will further be observed that when the purse is thus closed, the free edges of the pocket walls 8' and 10' at the open sides of the pockets are in contact with the central fold of the body wall 6' so that the open sides of the pocket are thus closed against the possible escape of the coins therethrough.

In Fig. 14 of the drawings, I have shown the closure tabs or extensions 13' on the end walls of one of the purse pockets extending inwardly as in Figs. 6 and 7, while in Fig. 15 I show these closure tabs at 13' extending outwardly from the lower edges of the pocket walls. In this construction, such tab extensions may be provided on the end walls of only one of the purse pockets, or if desired on the walls of both pockets.

In the use of this form of the device as indicated in Fig. 16, after releasing the fastening

means between the two pockets of the purse, it is held in the palm of the hand and pressure exerted against the opposite edges thereof to expand the end walls 10' of the pockets, thus fully opening the inner side of each pocket. 5 The opposite end portions of the body wall 6' are convergently inclined so that the coins will readily slide from one of the pockets upon the lower central portion of the body wall between the open sides of the two pockets. 10 After selecting the desired coins, the remainder may then be readily shifted into either one of the pockets, and the purse securely closed as shown in Fig. 12 of the drawings. 15 This form of the invention provides a very serviceable and convenient purse, as one of the pockets may be utilized as a container for bills, memoranda, cards and the like.

From the foregoing description considered 20 in connection with the accompanying drawings, the construction of my improved purse and its several embodiments here disclosed and the various advantages thereof will be readily understood. It is of course, apparent 25 that if desired, the last described double pocket form of the purse may likewise be provided with a suitable ornamental reinforcing lining of silk or other fabric material. The purse may be produced from various 30 ornamental leathers, and provides a simple and inexpensive article of this kind which may be utilized either as an adjunct for ladies' handbags or independently thereof as a pocket purse. While I have herein shown 35 and described several embodiments of the essential features of my invention, which are believed to be entirely practical for the purpose in view, it will nevertheless be understood that the same might also be incorporated 40 in various other structural forms, and I therefore, reserve the privilege of resorting to all such legitimate changes therein as may be fairly embodied within the spirit and scope of the appended claims.

45 I claim:

A purse comprising inner and outer pocket walls, said inner wall being of less width than the outer wall at the bottom of the pocket and 50 flexibly connected with said outer wall and decreasing in width from said connected end to its other free end, relatively foldable closures for the sides of the pocket connected to the opposite side edges of said inner wall and to the edges of said outer wall and expansible 55 under inward pressure applied to the opposite edges of said outer wall to widely space the inner wall at its free end from the outer wall and afford maximum accessibility to the pocket, and said foldable side closures having 60 relatively movable parts disposed between the inner and outer pocket walls at the bottom of the pocket and closing the corners thereof.

In testimony that I claim the foregoing as my invention, I have signed my name hereto.

65 CHARLES L'ENFANT.
